(57) **CLAIM**

The ornamental design for woodworking vise, as shown and described.

DESCRIPTION

FIG. 1 is a perspective view of the top, right and front of the design for the woodworking vise of this invention.

FIG. 2 is a perspective view of the bottom, rear and right side of the design for the woodworking vise shown in FIG. 1.

FIG. 3 is a left side view of the design for the woodworking vise shown in FIG. 1.

FIG. 4 is a right side view of the design for the woodworking vise shown in FIG. 1.

FIG. 5 is a front view of the design for the woodworking vise shown in FIG. 1.

FIG. 6 is a rear view of the design for the woodworking vise shown in FIG. 1.

FIG. 7 is a top plan view of the design for the woodworking vise shown in FIG. 1.

FIG. 8 is a bottom plan view of the design for the woodworking vise shown in FIG. 1; and,

FIG. 9 is a perspective view of the front, right side and top of the design for the woodworking vise shown in FIG. 1 shown installed on a woodworking bench.

The broken lines are included for the purpose of illustrating environment and form no part of the claimed design.
